[57] CLAIM

The ornamental design for a tree stand bow holder, as shown and described.

DESCRIPTION

FIG. 1 is a front elevational view of a tree stand bow holder showing our new design, the rear elevation being a mirror image thereof;

FIG. 2 is a right side elevational view thereof, the left side being a mirror image thereof;

FIG. 3 is a top plan view thereof;

FIG. 4 is a bottom plan-view thereof; and

FIG. 5 is an enlarged sectional view as taken on line 5—5 of FIG. 2.

FIG.1

FIG. 2

FIG. 3

FIG. 4

FIG. 5
